(57) **CLAIM**

We claim the ornamental design for a lug nut, as shown and described.

DESCRIPTION

FIG. 1 is a top perspective view of a lug nut, showing our new design;

FIG. 2 is a bottom perspective view thereof;

FIG. 3 is a front elevational view thereof;

FIG. 4 is an exploded top perspective view thereof;

FIG. 5 is an exploded front elevational view thereof;

FIG. 6 is an exploded rear elevational view thereof;

FIG. 7 is an exploded right-side elevational view thereof;

FIG. 8 is an exploded left-side elevational view thereof;

FIG. 9 is an exploded top plan view thereof; and,

FIG. 10 is an exploded bottom plan view thereof.

The broken lines showing a lug nut cap in FIGS. 1 and 2 depict environmental matter that forms no part of the claimed design.
